CLAIM

The ornamental design for a sportsball, as shown and described.

DESCRIPTION

FIG. 1 is a front view of a sportsball showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a view of the sportsball rotated between positions at FIG. 4 and FIG. 6, with the opposite side being the same; and,

FIG. 8 is a view of the sportsball of FIG. 7 rotated to better display the symmetry of the design, the opposite side being identical to the side shown.
